CLAIM

The ornamental design for an electronic key, as shown and described.

DESCRIPTION

FIG. 1 is a top, rear and left side perspective view of an electronic key showing my new design;

FIG. 2 is a bottom, front and left side perspective view thereof;

FIG. 3 is a rear elevational view thereof;

FIG. 4 is a left side elevational view thereof;

FIG. 5 is a bottom plan view thereof;

FIG. 6 is a front elevational view thereof;

FIG. 7 is a top plan view thereof; and,

FIG. 8 is a right side elevational view thereof.

The broken lines illustrate unclaimed portions and form no part of the claimed design.

The shade lines indicate contour and not surface ornamentation.

1 Claim, 2 Drawing Sheets(56)
